UNITED STATES PATENT OFFICE.

DALLAS W. STAINBROOK AND RAY H. WINTER, OF CALDWELL, IDAHO.

COMBINATION IMPLEMENT.

1,276,433.

Specification of Letters Patent. Patented Aug. 20, 1918.

Application filed August 6, 1917. Serial No. 184,728.

To all whom it may concern:

Be it known that we, DALLAS W. STAINBROOK and RAY H. WINTER, citizens of the United States, residing at Caldwell, in the county of Canyon and State of Idaho, have invented certain new and useful Improvements in Combination Implements, of which the following is a specification.

Our invention relates to a combination 10 implement and more particularly to a combination implement in the form of a pair of scissors and has as its primary object to provide an efficient and compact tool of this character which may be readily and easily 15 operated with great facility.

A second object of our present invention is to provide a combination implement or tool, which may be used to great advantage by dressmakers or tailors.

20 It is another object of our invention to provide a device of this general character which has the necessary devices for a dressmaker or tailor, all of which are mounted so that they can be readily used and in a way 25 which will avoid displacement of the various devices or articles.

It is another object of the invention to provide an implement of this character which is efficient and durable in use and 30 consists of few easily assembled operating parts, which can be manufactured and placed on the market at a minimum cost, and which may be used to great advantage by persons engaged in dressmaking or the like.

35 The above general objects and others will be discussed during the course of the following description and the inventive features will be claimed at the end thereof.

The invention consists of the construction 40 and arrangement of coöperating parts and the manner of operation all of which will be specifically set forth and illustrated in the accompanying drawings in which,

Figure 1 is a side elevation of a pair of 45 scissors or shears embodying our inventive idea.

Fig. 2 is an end elevation looking from the rear end of the finger engaging loops.

Fig. 3 is a view looking down upon the 50 upper edge of our improved scissors.

Fig. 4 is a sectional view taken on the line 2—2 of Fig. 1 and looking toward the needle holding handle and,

55 Fig. 5 is a slightly modified form of a chalk holding arrangement.

Referring to the drawings in which like

characters of reference indicate corresponding parts in all the views the numerals 5 and 6 indicate the blades of a pair of scissors or shears which are pivoted together and are 60 provided with the usual handles or finger loops 8. In this instance we have illustrated a pair of scissors but the invention is applicable to other forms of devices.

The inner pair of the handle or finger 65 loop 8 is formed with a longitudinal portion 9 which is provided with a longitudinal bore. This longitudinal portion constitutes a needle holding chamber and has a removable cap threaded in one end thereof, this cap 70 is designated by the numeral 10.

Formed in this finger loop or handle 8 at the inner end thereof is a recess 11 in which is rotatably mounted a tracing wheel 12 which rotates on the shaft 13 extending 75 transversely through this end portion of the handle or finger loop. Normally inclosing this tracing wheel is a cover or guard 14 which is hinged as at 15 and carries a resilient latch 16 for retaining the cover or 80 guard in position to overlie this tracing wheel.

The finger loop or handle 7 is provided with a recess or chalk retaining chamber 17 which accommodates the marking element 85 such as chalk. This piece of chalk is designated by the numeral 18. The chalk holding arrangement just described is clearly shown in Fig. 1. In Fig. 5 we have shown a slightly modified arrangement which consists of a recess similar to the form shown 90 in Fig. 1, which is for the purpose of accommodating the chalk, overlying which is a hinged cover 19.

Mounted in the recess in the forward end 95 of the handle or finger loop 7 is a substantially Y-shaped resilient clip which is in parallelism and alinement with the shank of the cutting blade 6. The ends of this clip 20 are longitudinally curved in opposite directions to facilitate the engagement of the clip with the thimble, that the clip is adapted to support, the thimble being designated by the numeral 21. It should be noted that the clip 20 is positioned just far enough 100 away from the shank of the blade 6 so that the open end of the thimble may rest upon this shank which will help to support the same.

These forms of the invention are merely 110 illustrative and it is to be understood that the inventive idea can be embodied in construc-

tions other than the ones herein specified. The construction can be altered and modified as the occasion may require in accordance with the herewith appended claims.

5 What is claimed is:

1. The combination with a pair of scissors having a recess formed in one of its handle loops, of a marker secured in said recess, a projection formed at one end of said recess, 10 and a curved resilient guard having one end pivotally secured to said finger loop at the opposite end of said recess and its free end engageable with said projection.
2. The combination with a pair of scissors

having a socket formed in one of its finger loops, of a thimble retaining member comprising a strand of wire bent upon itself to provide a shank adapted to be received in said socket and then separated to provide clamping arms curving outwardly to opposite sides of said shank.

In testimony whereof we affix our signatures in presence of two witnesses.

DALLAS W. STAINBROOK.

RAY H. WINTER.
